CLAIM

The ornamental design for a solar light, as shown and described.

DESCRIPTION

FIG. 1 is a first perspective view of a solar light showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is an atop view thereof;

FIG. 8 is a bottom view thereof; and,

FIG. 9 is an enlarged view of the selected portion in FIG. 2. The broken lines shown in the drawings illustrate portions of the solar light that form no part of the claimed design. The dash-dot-dash lines in FIGS. 2 and 9 represent the boundaries of the enlarged view and form no part of the claimed design.
